CLAIM

The ornamental design for a funnel, as shown.

DESCRIPTION

FIG. 1 is a perspective view of a funnel, showing a typical embodiment of the new design.

FIG. 2 is a rear, elevational view of the funnel.

FIG. 3 is a front, elevational view of the funnel.

FIG. 4 is a right side, elevational view of the funnel; the left side view is a mirror image of the right side.

FIG. 5 is an enlarged bottom, plan view of the funnel; and, FIG. 6 is a top, plan view of the funnel.
